(57) CLAIM

We claim the ornamental design for the sandal handle, as shown and described.

DESCRIPTION

FIG. 1 is the front view of the sandal handle showing our new design;

FIG. 2 is the front perspective view thereof;

FIG. 3 is the rear perspective view thereof;

FIG. 4 is the back elevation view thereof;

FIG. 5 is the front view of the sandal handle. The broken lines in FIG. 5 showing the sandal handle in use illustrates environment and forms no part of the claim.

FIG. 6 is the back view of the sandal handle. The broken lines in FIG. 6 showing the sandal handle in use illustrates environment and forms no part of the claim; and,

FIG. 7 is a perspective view of the sandal handle in use. The broken lines in FIG. 7 showing the sandal handle in use illustrates environment and forms no part of the claim.
